UNITED STATES PATENT OFFICE.

WILLIAM C. HELMS, OF LINCOLNTON, NORTH CAROLINA.

HOT-AIR FIREBACK.

Application filed May 15, 1928. Serial No. 277,890.

My invention relates to hot air fire backs, for use in open fire places.

In accordance with my invention, I provide a hot air fire back which may be installed in the ordinary open fire place of a chimney, without materially altering the chimney or room. The fire back embodies a shell or casing having means for introducing cold air into the lower portion thereof from the room and discharging the heated air from the upper portion of the same into the room. The front wall of the casing is equipped with a plurality of vertically arranged pockets, the bottom walls of which are preferably vertically inclined, and serve to deflect the heat upwardly and outwardly into the room. A grate is arranged adjacent to the front of the vertical pockets for holding the fuel, such as coal, wood or the like. Arranged above the vertical pockets are a plurality of pockets, which may be vertically or horizontally arranged. In the preferred embodiment of the invention, the upper pockets are vertically arranged, and each pocket is divided into a plurality of cells by means of preferably inclined partitions. The heated gases or products of combustion passing from the lower pockets, travel into the upper pockets or cells thereof, and circulate therein, and finally discharge through tubes or flues arranged near the top of the upper pockets. By virtue of the construction and arrangement of the several parts of the apparatus, the maximum heating area is provided, and the maximum heat exchange effected between the products of combustion and the air. The lower pockets are preferably carried upon a removable frame, whereby they may be removed as a unit so that new pockets may be substituted in the event that the lower pockets should burn out. The device is neat and attractive in appearance and efficient in operation.

In the accompanying drawings, and in which like numerals are employed to designate like parts throughout the same,

Figure 1 is a front elevation of a hot air fire back embodying my invention,

Figure 2 is a transverse vertical section taken on line 2—2 of Figure 1,

Figure 3 is a horizontal section taken on line 3—3 of Figure 1,

Figure 4 is a similar view taken on line 4—4 of Figure 1,

Figure 4' is a detailed side elevation of

one end of the grate showing the attaching means therefor,

Figure 5 is a front elevation of a fire back embodying a modification of the invention, and,

Figure 6 is a central vertical section through the same.

In the drawings, wherein for the purpose of illustration, is shown a preferred embodiment of my invention, the numeral 10 designates the open fire place of a chimney, arranged within a room. The fire back embodies a casing 11, including side walls 12, connected at their lower ends by a bottom wall 13, and at their upper ends by a top wall 14. The casing includes a front wall 15. The walls are preferably cast integral, while the invention is not necessarily restricted to this construction, as the casing may be made of sheet iron or the like. The back of the casing is closed by a cover 16, preferably formed separate therefrom, and bolted or otherwise rigidly attached thereto, for forming a gas-tight joint.

The front wall 15 is provided in its lower portion with a rectangular relatively large horizontal opening 17, the walls of which are preferably bent inwardly, providing a recess or socket 18. This rectangular socket is adapted to receive a rectangular flange 18', the outer face of the frame being preferably flush with the outer face of the front wall 15, these parts being held together by bolts 20 or the like. Preferably cast integral with the flange 18', are relatively deep vertically arranged pockets 21. The bottom walls of these pockets are preferably longitudinally curved, and produce upper and lower wall sections 22 and 23. The lower wall sections 23 are inclined upwardly and rearwardly, while the upper wall sections 22 are inclined downwardly and rearwardly. The upper wall sections 22 serve to reflect the heat outwardly into the room.

The flange 18' is provided with U-shaped sockets 24, at its vertical edges, and these sockets detachably receive downwardly turned hooks 25 carried by a grate 26. This grate is arranged at an elevation whereby its bottom is spaced a slight distance above the lower ends of the pockets 21, whereby air for combustion, may readily pass to the fuel, and also into the pockets 21.

Preferably cast integral with the upper portion of the front wall 15 are vertical

pockets 27, the lower ends of which are spaced from the tops of the pockets 21. These vertical pockets are relatively deep and each pocket embodies a curved bottom wall, providing a lower inclined bottom wall section 28, and an upper inclined bottom wall section 29. The wall section 28 is inclined downwardly and the wall section 29 is inclined upwardly, as shown. The pockets 27 are preferably in alignment with the pockets 21. The front wall 15 is longitudinally curved and by virtue of this arrangement, the upper pockets extend forwardly over the lower pockets, to some extent, as shown. Each pocket 27 is provided with inclined partitions 30, preferably cast integral therewith, providing a plurality of cells 31, which are closed except at their outer ends. The partitions 30 preferably have their lower ends extended slightly forwardly beyond the pockets, to catch the products of combustion and to more readily guide the same into the cells. The partitions 30 are inclined downwardly, as stated, and the heated gases or products of combustion enter the various cells, and travel upwardly therein, and upon cooling, travel downwardly therefrom and discharge out of the same, into the presence of the ascending heated products of combustion. By this means, the retarded circulation of heated gases or products of combustion occurs in each cell, thereby effecting the maximum heat exchange.

The numeral 32 designates upstanding tubes or flues, the lower ends of which lead into the uppermost cells 31, and the upper ends of which pass through the top wall 14, and discharge exteriorly of the casing 11, into the chimney. A second set of tubes or flues 33 are preferably provided and are arranged above the tubes 32, in staggered relation, as shown. The lower ends of the tubes 33 pass through and beyond the front wall 15 and their upper ends pass through and beyond the top wall 14.

Air is supplied into the bottom of the casing 11 through an inlet pipe 34, preferably extending beneath the top of the bottom wall 36, and into the room, this pipe 50 having its intake end covered by a register 37 or the like. Heated air from the casing 11 discharges from the top thereof through a horizontal pipe 38, which passes through a suitable opening in the front wall of the chimney, and hence into the room. This opening may be covered by an ornamental grate or the like.

In the operation of this form of apparatus, the fuel is burned in the grate 26, and the products of combustion pass upwardly into and through the pockets 21, heating the walls thereof. Some of the heat is reflected upwardly and forwardly into the room, by the inclined upper wall sections 22. The heated gases or products of combustion pass

upwardly over the inclined front wall 15, and enter the cells 31, circulating therein, as explained, and traveling upwardly and discharging through the flues or tubes 32 and 33 into the stack of the chimney. The air to be heated enters the casing 11 through the pipe 34, and travels upwardly therethrough in contact with the heated pockets 21 and 27, whereby an efficient heat exchange is effected between the heated pockets and the air. The air also travels between the tubes 32 and 33 and is further heated thereby. The air finally discharges through the pipe 38 into the room.

In Figures 5 and 6, I have shown a modification of my invention. The same casing 11 is provided, and the same flange 18' with the vertical pockets 21 are employed, this frame being attached to the front wall 15, as explained in connection with the first form of the invention. The grate 26 is employed and is detachably connected with the flange 18'.

In this form of the invention, the front wall 15 is not provided with the vertical pockets 27, but horizontally arranged pockets 27' are provided, preferably cast integral therewith. These pockets 27' are relatively deep and have inclined bottom and top walls 28' and 29', as shown. The upper inclined portion of the front wall 15 is equipped with tubes or flues 30', extending to the front surface thereof, and these tubes or flues project through and beyond the top wall 14, as shown.

The casing 11 is equipped with the same air intake pipe 34, at its bottom, and the air outlet pipe 38 at its top.

The operation of this form of the invention is similar to that of the first form. The heated gases or products of combustion pass upwardly through the lower vertical pockets 21 and enter the horizontal pockets 27', circulating therein, and finally discharging upwardly through the tubes 30'. The air entering the lower end of the casing 11 passes upwardly therethrough in contact with the several pockets, effecting an efficient heat exchange therewith.

It is to be understood that the forms of my invention, herewith shown and described, are to be taken as preferred examples of the same, and that various changes in the shape, size and arrangement of parts may be resorted to without departing from the spirit 115 of my invention, or the scope of the subjoined claims.

Having thus described my invention, I claim:

1. A hot air fire back for an open fire 125 place, comprising a casing provided near its lower end with an air intake and near its upper end with an air outlet, said fire back having a forwardly inclined front wall, means providing a plurality of spaced verti- 130

- cal pockets arranged in the lower portion of the front wall, each pocket having an upper inclined wall section adapted to reflect heat into the room, means providing spaced vertical pockets in the upper portion of the front wall, each vertical pocket having inclined upper and lower wall sections, partitions arranged within each upper pocket and serving to divide the same into cells, and tubes leading into the upper pockets and extending through the upper portion of the casing and discharging to the exterior thereof, and means arranged forwardly of and near the lower pockets for supporting fuel.
- 5 2. A hot air fire back for an open fire place, comprising a casing provided near its lower end with an air intake and near its upper end with an air outlet, said fire back having a forward front wall, means providing a plurality of spaced vertical pockets arranged in the lower portion of the front wall, each pocket having a lower bottom section inclined downwardly and an upper inclined upwardly, the upper section being adapted to reflect heat into the room, means providing spaced vertical pockets in the upper portion of the front wall, each upper pocket having a lower wall section inclined downwardly and an upper wall section inclined upwardly, a plurality of spaced partitions arranged within each upper pocket and projecting forwardly beyond the same, a plurality of tubes extending into the upper ends of the upper pockets and passing through the upper portion of the casing and extending to the exterior thereof, and fuel supporting means arranged near and in advance of the lower pockets.
- 10 3. A hot air fire back for an open fire place, comprising a casing provided near its lower end with an air intake and near its upper end with an air outlet, said fire back having a forward front wall, means providing a plurality of spaced vertical pockets arranged in the lower portion of the front wall, each pocket being generally U-shaped, means providing spaced vertical pockets in the upper portion of the front wall, each upper pocket being generally U-shaped, a plurality of spaced downwardly inclined partitions arranged in each upper pocket, a plurality of tubes leading into the upper ends of the upper pockets and passing through the upper portion of the casing and extending to the exterior thereof, and means for supporting fuel in proximity to the front of the lower pockets.
- 15 4. A hot air fire back for an open fire place, comprising a casing provided near its lower end with an air intake and near its upper end with an air outlet, said casing having a forwardly inclined front wall, means providing spaced vertical generally U-shaped pockets in the lower portion of the front wall, means providing spaced vertical generally U-shaped pockets in the upper portion of the front wall, the upper pockets being disposed above the lower pockets and arranged in advance thereof, spaced inclined partitions within each upper pocket for forming a plurality of cells, flues leading into the upper ends of the upper pockets and passing through the upper portion of the casing, and fuel supporting means arranged near and in advance of the lower pockets.
- 20 5. A hot air fire back for an open fire place, comprising a casing having an air intake near its lower end and an air outlet near its upper end, said casing having a front wall which inclines forwardly toward its upper end, means providing spaced vertical pockets in the lower portion of the front wall, means providing upper pockets in the upper portion of the front wall, the upper pockets extending rearwardly from the front wall across the major portion of the transverse area of the casing, said upper pockets having inclined upper and lower walls, tubes extending through the upper portion of the casing and receiving products of combustion from the pockets, and fuel supporting means arranged near and in advance of the lower pockets.
- 25 6. A hot air fire back for an open fire place, comprising a casing provided with an air intake near its lower end and an air outlet near its upper end, said casing having a front wall provided in its lower portion with a relatively large opening, an integral unit for insertion within the relatively large opening including a frame and spaced vertical pockets carried thereby, said unit being removably mounted within the opening, and outlet means for the products of combustion traveling forwardly of the front wall.
- 30 7. A hot air fire back for an open fire place, comprising a casing provided with an air intake near its lower end and an air outlet near its upper end, said casing having a front wall provided in its lower portion with a relatively large opening, an integral unit removably mounted within the opening and including a flange and spaced inwardly projecting pockets, means providing pockets above the lower pocket and extending inwardly from the front wall, outlet means to receive products of combustion from the upper pockets, and fuel supporting means arranged near and in advance of the lower pockets.
- 35 8. In testimony whereof I affix my signature.
- 40 WILLIAM C. HELMS.
